UNITED STATES PATENT OFFICE.

JOHN W. DANFORTH, OF BUFFALO, NEW YORK.

GAS-STOVE.

SPECIFICATION forming part of Letters Patent No. 443,088, dated December 23, 1890.

Application filed April 1, 1890. Serial No. 346,211. (No model.)

To all whom it may concern:

Be it known that I, JOHN W. DANFORTH, a citizen of the United States, residing in Buffalo, in the county of Erie and State of New York, have invented certain new and useful Improvements in Gas-Stoves, of which the following is a specification.

The object of my invention is to produce a compact and convenient gas-stove of simple construction and having every portion easy of access; and it consists of a gas cooking-range in which coal-gas, gasoline, or natural gas may be used, all of which will be fully and clearly hereinafter described and claimed, reference being had to the accompanying drawings, in which—

Figure 1 is a front elevation, the vertically-sliding oven-door being omitted. Fig. 2 is a side elevation. Fig. 3 is a horizontal section 20 on line *a b*, Fig. 1; and Fig. 4 is a sectional elevation in or about line *c d*, Fig. 1, through the water-reservoir and flues. Fig. 5 is a horizontal section in or about line *a b*, Fig. 1, the vertical walls of the oven being omitted, so 25 as to show the openings in the table *3^a*, which register with the vertical passages through the oven-walls.

In said drawings, 1 represents the base-frame, upon which the burners, oven, water heater or reservoir, and other parts are supported. This frame-work is preferably constructed of cast-iron, as the cheapest and most suitable material, and is provided with a series of slideways 2 to receive the removable shelves 3 and with a top *3^a*. The shelf 3 is used for pots and kettles or other like purposes. The shelf *3^a* forms a part of the case surrounding the burners 26, the object being 35 to retain the heat and gases and cause them to go upward through flues, and to prevent 40 them from coming out into the room.

On the top of the lower or supporting frame 1 is secured the upper frame-pieces 4 by the bolts 5, which pass through the top *3^a* and 45 then into the lower frame. This upper frame is so formed at the top as to embrace and hold the water-reservoir 6, substantially as shown in Figs. 1 and 2, and it is provided with slideways 7 and 8 to receive one or more 50 shelves 9 and 10. The shelves 10 or the shelves that go on the slideways 8 are used

for warming plates or other analogous purposes.

It will be noticed that the height of the oven can be adjusted by placing the shelf 9 55 on either of the slideways 7.

In baking some things a quick heat is required; this can be done by contracting the size of the oven. Again, some things are better done by baking them by heat applied at 60 the bottom first; this can be done by the heat from the burners 26, after which the burners 34 can be started, which will give the necessary heat at the top when the shelf 9 is removed. 65

The upper ring-shaped portions 11 receive and hold the water-reservoir 6, the ends of which pass through them, as shown in Figs. 1 and 2.

Around the reservoir 6 is a jacket of sheet 70 metal 12, which passes up from the point 13 to the back part of the top 14, and is provided with an outlet or vent pipe 15. A back plate of sheet metal 16 covers the back from the point 14 down to the table *3^a*. This construction leaves a flue 17, surrounding the water-reservoir 6, substantially as shown in Fig. 4. 75

The water-reservoir may be made of plate copper, or of any suitable well-known material, and, if desired, it may be made up of a 80 series of coils of pipe in any well-known way; but the construction shown is preferred. It is provided with inlet-pipes 18 and outlet-pipes 19. (Shown in Figs. 1 and 2.)

The oven consists of the three double walls 85 20, 21, and 22 and a vertically-sliding door 23, adapted to slide up and down in the vertical grooves 24. (Shown in Fig. 3 and by dotted lines in Fig. 1.) This sliding door 23 is of the same height as the swinging door 22, which extends up to the line or point 40. (Shown in Fig. 1.) The object of this construction is to leave room to withdraw the broiler 37 and its shelf 36, when required, and to leave the door 23 only high enough to 90 just pass above the shelf 9, which acts as the top of the oven, and is removed when it is required to use the upper burners 34 and lower burners 26 either separate or together while the oven-door is closed. In Fig. 2 the door 23 is shown as raised up to the top of the slide-way, and in Fig. 4 it is shown as nearly down 95 100

- to its place. This door 23 when closed is never high enough to cover or inclose the burners 34, so that sufficient air is at all times admitted thereto. These double walls form flues 25, through which the heat and all the products of combustion from the lower burners 26 (which are placed below the table 3^a, as shown) pass up around the oven through the flues 25.
- 10 Whenever it becomes necessary to use the whole top of the stove without the oven for cooking or other purposes, the double partition or wall 22, which is swung on hinges 27, (see Fig. 3,) is turned back into the position 15 shown by the dotted lines 28 in said Fig. 3, thereby leaving the whole top of the stove to be used when the oven is not required.
- When the wall or partition 22 is closed, as shown in Figs. 1 and 3, it is secured in that 20 position by putting in a shelf 10 on either of the slideways 8.
- The shelves 3, 9, and 10 are easily removable, being made so as to be slid in on the various slideways 2, 7, and 8.
- 25 The burners 26 are connected by pipes 30 with the air-mixers 31, which receive the heating-gas through the tube 32, the flow of which is controlled by the stop-cocks 33.
- Just below the water-reservoir 6 are two 30 burners 34 and 35, each of which is provided with an air-mixer 31, and a stop-cock 33, for controlling the flow of gas.
- Below the burners 34 is a shelf 36, upon 35 which is placed a meat-broiler or toaster 37. Both the shelf and the broiler or toaster are easily removable when required.
- By this construction of the stove it will be seen that nearly all the heat from the burners or from the operation of the stove will be 40 caught within the jacket 12, and is thus utilized in heating the water-reservoir 6 after having done its work below either in cooking or baking.
- 39 in Fig. 4 represents the end of a trough 45 to catch any drip that may come from the boiler. It extends the whole length of the boiler.
- In Fig. 5, 25^a represents the openings through the top plate 3^a, which register with 50 the passages for the products of combustion through the walls 20, 21, and 22, said walls

being omitted in said Fig. 5, so as to show these openings more clearly.

I claim—

1. In a gas cooking-stove, the combination, with the upper and lower supporting-frames, of a warming-chamber at one side of the stove, an oven located at the opposite side, composed of double walls forming flues through which the heat passes, a sliding door forming the front removable side of the oven, a removable shelf 9, forming the top of the oven, a water-reservoir located in the top of the upper frame, a jacket inclosing the water-reservoir and forming a flue between it and the reservoir, and a series of burners located below the stove-top, from which the heat passes to the warming-chamber and to the oven-flues and water-reservoir, substantially as described.

2. In a gas cooking-stove, the combination, with the other walls of the oven, of a hinged wall forming one wall thereof, adapted to be thrown back to one side so as to expose the whole top of the stove for use, substantially as described.

3. In a gas cooking-stove, an oven consisting of three hollow walls open at the top and bottom, one of the walls being hinged so as to be thrown back to expose the whole top of the stove, and a sliding door adapted to slide vertically in slideways in the two opposite walls, substantially as described.

4. A gas cooking-stove consisting of three sections—a lower section, in which the burners are located, a section in which the oven and warming-chambers are located, and top section, in which is located the water-reservoir—substantially as and for the purposes described.

5. A gas cooking-stove having the water-reservoir located at the top and an intermediate cooking and baking section below it, a series of burners located below the intermediate section, and a means for admitting or shutting off the gas, whereby the heat after 9 being used in the cooking and baking section passes up to the water-boiler, substantially as described.

JOHN W. DANFORTH.
